CARD TITLE HOLDER

Harry Herbert Vanderzee, Grand Rapids, Mich.,
assignor to Ami, Incorporated, Grand Rapids,
Mich., a corporation of Michigan

Original application February 2, 1948, Serial No.
5,854. Divided and this application October 26,
1948, Serial No. 56,493

5 Claims. (Cl. 40—96)

1

This invention is directed to the provision of an improved title holder adapted, for example, to display title identification cards of the multiple record selections available on an automatic phonograph, and the present specification is a division of my copending application Serial No. 5,854, filed February 2, 1948.

In any automatic phonograph or the like it is of obvious advantage to have means for displaying the titles of the various records carried in the machine in such a manner that they may be large, well illuminated and held at a convenient reading angle. This has heretofore been quite difficult of accomplishment in machines capable of reproducing a large number of selections, however, since if the individual title cards are made large enough to be easily readable at a convenient distance the overall dimensions of the title holder display also become so large as to be objectionable where space is limited. This is particularly true in connection with remote control stations for an automatic phonograph wherein the control mechanism is housed within a small box or cabinet having a very limited area in which the titles of the available selections may be presented.

It is accordingly a primary object of this invention to provide a novel and improved holder for cards such as the title cards identifying phonograph record selections, so that the individual cards may be relatively large, yet wherein the parts are so arranged that a large number of cards may be held in compact arrangement so that the device is well suited to installations where the area available for title display is limited.

A further object of the invention is to provide a title holder well suited to use in remote control units, for example, where interior space to house the operating mechanism is also limited. Specifically, this contemplates a remote control wall box for a phonograph wherein the titles are mounted on an endless chain arranged to extend around the working parts of the mechanism within the box, so that the structures of the title holder and of the selection mechanism may be closely nested together. Thus it is feasible to provide a comparatively small unit having a sufficiently compact arrangement of parts so that its outer dimensions may be held within permissible limits without unnecessarily limiting the size of the individual working parts.

Another important object is to provide a title card holder designed so that the individual cards are held at a convenient reading angle and can be adequately illuminated, yet so arranged that

2

the cards are illuminated without objectionable shadows or glare.

The foregoing objects are accomplished by the teachings of this invention by the provision of a title holder in the general form of a broad, flat chain or belt made up of a plurality of long narrow slats pivoted to each other but so designed that the individual slats each lie at an acute angle with respect to the general plane of the belt. 10 This holds the individual title cards at a convenient reading angle and aids in providing adequate illumination to their face surfaces, since light projected against the rear face of the belt may be reflected downwardly from a polished reflective surface in the back of each slat onto the face of the identification card mounted on the next slat below. The invention also contemplates the provision of a title holder of the chain form described, with the chain itself mounted between 15 large upper and lower pairs of sprockets to provide a vertical display surface along the front span of the chain with the rear span spaced well back of the front, to define a relatively large interior space within the loop of the chain. This 20 space may conveniently house any desired form of remote control mechanism so that the title holder and the operating mechanism nest together to require a minimum amount of space.

The form of the invention chosen as best illustrative of the inventive concept herein is illustrated in detail in the drawings of this specification wherein:

Figure 1 is a front elevational view of a phonograph wall box; that is, a remote control selector unit adapted to control the operation of an automatic phonograph;

Figure 2 is an enlarged sectional view taken substantially on the plane of the line 2—2 of Figure 1 showing the construction of the title holder disclosed herein and the preferred manner of mounting the title holder within the housing of the wall box; and

Figure 3 is a face view of a few links of the title holder chain, showing the individual slats thereof with the longitudinal channels in which the title identification cards are supported.

In the embodiment of the invention here shown the title holder according to these teachings is incorporated into a wall box remote control unit 50 including the housing 10 having one or more coin chutes 11 so that the action of the machine can be initiated by the insertion of a coin. The housing has a transparent front window 12 so that the various title identification cards 43 listing the 55 records available in the machine may be seen

through the window. According to this invention these title cards are mounted on an endless chain so that they may be passed before the window in turn by the rotation of selector knobs 15 which are inwardly geared to the sprockets on which the chain is mounted. Thus the various cards representing the records available in the machine may be moved upwardly or downwardly across an indicator mark 14; it being understood, of course, that by positioning any title card against the selector 14 and actuating the push button 16 the remote control mechanism of the wall box will function to actuate the phonograph in a manner to play the record selected.

The title holder is in the form of an endless chain 31, the upper end of which passes over and is carried on a pair of sprockets 32 fixed at the opposite ends of a horizontal shaft 33. The chain loop hangs down from the sprockets 32 to similar lower sprockets 61, and is positioned with the front span immediately inside the glass of the window 12 and its back span spaced well back from the front span to provide an open space within the chain loop for mounting the working parts of the selector mechanism. The shaft 33 is journaled in a pair of side plates 34, which are in turn supported by any suitable means. The sprockets 32 each include a hub in the form of an outwardly projecting gear 37, each of which overhangs the brackets 21 and mesh with one of a pair of fiber gears 38 carried on the inner ends of the stub shafts 39 of the selector knobs 15. The chain 31 consists of a multiplicity of identical links, each having a flat channel portion 41 with side flanges 42 along its upper and lower edges, so that a title card 48 carrying the name of one of the record selections may be slid into position from the right-hand end of the channel. A stop portion 44 is struck from the back of the panel (Figure 3) at a point near its left-hand edge to limit the inward movement of the title cards and to locate a selection number 45, which may be in the form of a plastic card also slid into the channel and held in place by a small tab 50.

The opposite ends of the individual channels are bent back to form link portions 47 and are pierced so that the several links may be joined by pins 48 to form a continuous chain. These pins are preferably headed, as indicated at 49, and small tabs 51 are struck from the metal of the links to overlie the head of each pin and prevent the chain from becoming disassembled. The link portions 47 of each channel are not exactly parallel with each other, but diverge slightly from the upper ends toward the lower ears 52 so that the lower ears of each link may overlie the upper portions of the adjoining link without binding. The lower loop of the chain passes around a lower pair of sprockets 61 mounted on a floating axle shaft 62, which extends through a pair of bayonet slots in the side plates 34.

It is to be noted that the card receiving surface of the individual channels is not parallel with the length of the chain, but is at an acute angle thereto, so that the lowermost edge of each of the channels behind the window 12 overhangs the uppermost edge of the channel immediately below it. This arrangement defines a substantial gap 53 between adjacent channels, and permits light to pass through the chain from a light source behind it, but since the back surface of each channel is brightly polished, the back surfaces of each act as a mirror to reflect 75

this light back downwardly to the face of the title selection cards. Thus all of the cards behind the window may be brilliantly illuminated, yet displayed without glare and without a visible source of illumination.

Illumination for the title cards is provided by a plurality of small incandescent lamps 54 mounted in suitable sockets between a reflector 55 and a translucent diffusing sheet 56, which is secured to the opposite ends of the reflector and positioned in a plane immediately behind the forward span of the chain, and since there are several lamps positioned at different points along the forward span of the chain it will be seen that their combined effect will be to produce substantially uniform lighting of the diffusing plate, from which the light is directed to the polished back surfaces of each channel and back down on the title cards.

Any desired selection on the phonograph may be made by manually manipulating one of the knobs 15, to rotate shaft 33 and pinion 38 to rotate the gears 37 and sprockets 32 and move the chain 31 to bring the desired title card adjacent the indexing marker 14. A step-by-step motion is accomplished by a detent including a notched wheel 57 on the inner face of one of the sprockets 32 and a detent roller 58 on a spring urged lever or rocker arm 59. This detent facilitates accurate alignment of the title cards with the marker 14, and prevents the chain from coming to rest in a position between two of the cards.

From the foregoing it will be apparent that the teachings of this invention depart from prior expedients in a manner to facilitate the effective display of the title cards in such a manner that the individual titles may be relatively large and consequently easy to read, yet a comparatively large number of title cards can be incorporated into a machine in a compact and space-saving arrangement.

Further, each individual title card is held at a convenient reading angle, yet is clearly illuminated by diffused, reflected light, emanating from a glare proof source. In addition, the title holder is of relatively simple mechanical construction in which each of the individual links are identical with the others so that it is well suited to mass production methods of manufacture and can be produced economically on conventional types of machinery, yet will be rugged in use and not greatly subject to wear or damage. The endless loop form in which the holder is here disclosed is of particular advantage in providing of space saving nesting arrangement with the operating parts of the remote control mechanism, since the title holder lies closely adjacent the walls of the housing and extends around the operating mechanism. This provides adequate space for the selector mechanism within the confines of the chain loop itself.

Having thus described my invention what I claim as new and desire to secure by United States Letters Patent:

1. A title holder comprising an endless chain consisting of multiple links, with each link having a relatively long, narrow longitudinal channel extending transversely of the length of the chain; the chain being supported on a pair of sprockets at the upper end and having front and back spans hanging downwardly from the sprockets; with the surface of each channel at an acute angle with respect to the length of the chain span, whereby the lowermost edge of each channel in

the front span overhangs the uppermost edge of the next lower channel; together with title cards in the channels, and an inclined reflector surface on the rear of each channel adapted to direct light downwardly and rearwardly to illuminate the title card in the next lower channel.

2. A title holder comprising an endless chain consisting of multiple links, with each link having a relatively long, narrow longitudinal surface extending transversely of the length of the chain; the chain being supported on a pair of sprockets at the upper end and having front and back spans hanging downwardly from the sprockets; with the surface of each link at an acute angle with respect to the length of the chain span, whereby the lowermost edge of each link in the front span overhangs the uppermost edge of the next lower link; together with a reflector surface on the rear of each link adapted to direct light downwardly and rearwardly to illuminate the next lower link.

3. A title holder comprising a chain consisting of multiple links, with each link having a relatively long, narrow longitudinal channel extending transversely of the length of the chain; the chain being supported on a pair of sprockets at the upper end and having a substantially vertical span hanging downwardly from the sprockets; with the surface of each channel at an acute angle with respect to the length of the chain span, whereby the lowermost edge of each channel in the front span overhangs the uppermost edge of the next lower channel; together with title cards in the channels, and an inclined reflector surface on the rear of each channel adapted to direct light downwardly and rearwardly to illuminate the title card in the next lower channel.

4. A title holder comprising an endless chain consisting of multiple links, with each link having a relatively long, narrow longitudinal channel extending transversely of the length of the chain with the surface of each channel at an acute angle with respect to the length of the chain, whereby the lowermost edge of each channel overhangs the uppermost edge of the next lower channel to permit light to pass through the chain; together with title cards inserted in the channels.

5. A title holder comprising a chain consisting of multiple links, with each link having a relatively long, narrow longitudinal channel extending transversely of the length of the chain with the surface of each channel at an acute angle with respect to the length of the chain, whereby one edge of each channel overhangs the adjoining edge of the next adjacent channel to permit light to pass through the chain; together with title cards inserted in the channels.
